UNITED STATES PATENT OFFICE.

FREDERICH ALEITH, OF CASSELTON, NORTH DAKOTA, ASSIGNOR OF ONE-HALF TO J. M. ALEITH, OF SAME PLACE.

COMBINATION MATCH-BOX, CIGAR-CUTTER, &c.

SPECIFICATION forming part of Letters Patent No. 585,457, dated June 29, 1897.

Application filed September 18, 1896. Serial No. 606,231. (No model.)

To all whom it may concern:

Be it known that I, FREDERICH ALEITH, residing at Casselton, in the county of Cass and State of North Dakota, have invented a new and useful Combination Match-Box, Cigar-Cutter and Ash-Receiver, of which the following is a specification.

This invention relates generally to a match box or safe, and more particularly to a combination match box or safe, cigar-cutter, and ash-receiver, the object being to provide a combination device of the character described in which the plunger which operates the match-feeding device will also operate the blade for cutting off the end of a cigar.

Another object of the invention is to provide a feeding device which will deliver only one match at a time and cannot be thrown out of order.

Another object is to provide a detachable ash-receiver which can be removed and the ashes discharged therefrom; and a still further object is to provide a detachable receiver for holding the burned matches, which receiver can also be detached and the matches thrown therefrom.

The invention consists in certain details of construction and novelties of combination, all of which will be fully described hereinafter and pointed out in the claim.

In the drawings forming a part of this specification, Figure 1 is a perspective view of the complete device. Fig. 2 is a vertical longitudinal section. Fig. 3 is a side view, the side plate being removed in order to expose the cutting and feeding mechanism. Fig. 4 is a transverse sectional view on the line 4-4 of Fig. 3. Fig. 5 is a detail perspective view of the vibrating feed-drum. Fig. 6 is a detail side elevation of a mutilated pinion employed for vibrating the feed-drum.

In carrying out my invention I employ a base A, upon which is arranged the vertical box or casing B, said box or casing having a hopper C in the upper end thereof, a catch-chamber D in the lower end thereof, and an intermediate chamber E, within which is journaled the vibrating roller F, said roller having a groove G produced therein to receive a single match from the hopper C, which match is discharged through an opening H, produced

in the side of the box or casing, when the feed-drum is properly vibrated, and in order to vibrate said drum for the purpose of feeding the matches from the hopper I employ a mutilated pinion I, which is mounted upon one end of the drum, said pinion resting in the recess I', produced in the side of the box, and meshing with the said mutilated pinion is a plunger-rod K, having rack-teeth K', which mesh with the teeth of the mutilated pinion, and as the plunger-rod is forced down the feed-drum will be vibrated to discharge a match into the match-receiving receptacle L, arranged at one side of the main box or casing B.

The plunger-rod K slides in a vertical recess K² and is normally projected upwardly by means of a spring K³, held in the recess K⁴, cut into the side of the box or casing B.

The lower end of the plunger K is formed with a cutting-blade K⁵, by means of which the butt-ends of the cigars are severed, said ends being projected through an opening K⁷, produced in the side of the box, which openings lead directly into the catch-chamber D, which is intended to catch the severed ends of the cigar and retain them until it is desired to remove them from the device, said butts being removed through an opening D', produced in the base or bottom of the chamber D, which opening is normally closed by a pivoted bottom D², turned by means of a suitable handle D³.

A metallic side plate B' is secured to the recessed side of the box or casing B for the purpose of holding the operating plunger and spring in their proper places, and this side plate B' is provided with openings B², which register with the openings K⁷ and through which the butt-end of the cigar is to be introduced for the purpose of having the cutting-blade sever the end therefrom.

The hopper C has a cover C' fitted thereon, said cover having a pivoted locking-bar C², which is adapted to be turned into engagement with the side recesses C³ for the purpose of locking the top thereon, said locking-bar being removed by means of a button C⁴, which projects through the top of the hopper. The top of the hopper is also provided with an opening C⁵, through which the upper end

of the plunger-rod passes, said plunger-rod being provided with a detachable cap-piece or head K⁸.

The mutilated pinion is rigidly fixed to one end of the feed-drum in any suitable manner; but in practice I prefer to provide the bore or central opening of the said pinion with a series of inwardly-projecting teeth which engage a corresponding series of indentations in the end of the feed-drum, it being of course understood that the said feed-drum is provided with a reduced projecting end upon which the mutilated pinion is secured.

The sides of the box or casing are extended along the base, as shown at B³, and between such extended sides is arranged a detachable ash-receiver M, having a bar M', upon which to knock the ashes.

At the side of the box or case opposite to the operating mechanism is arranged a receptacle N for receiving the burned matches, said receptacle being detachably secured to the box B by means of hooks N', which engage the slots N² and the pins N³ located therein, said receptacle being readily removable as well as the ash-receptacle in order that they may be thoroughly cleaned, when desired.

Across the bottom of the chamber E, in which the vibrating feed-drum is journaled, is a stop-rib O, and the feed-drum is provided with projecting portions O' and O², which engage the said stop-rib O and limit the forward or backward movement of the feed-drum, thereby preventing the said drum from moving too far in either direction and causing it to stop at the proper positions to receive and discharge the match.

Now in operation, when it is desired to fill the hopper with matches the button upon the top of hopper is revolved to unlock the said top, which is then turned around upon the plunger-rod until the hopper is opened. This hopper is then filled with matches, the top turned back and locked. When a person desires a match, it is only necessary to press down upon the plunger-rod, which, carrying

the rack-teeth, meshes with the mutilated pinion, vibrates the feed-drum, and discharges a single match into the match-receiving receptacle at the end of the base. At the same time the end of the cigar can be severed by merely inserting the said end into one of the openings in the side of the box or case, and as the plunger-rod descends in operating the feed-drum the sharp blade at the lower end thereof will sever the butt-end of the cigar, said end falling into the catch-chamber arranged beneath the match-feeding drum.

The base can be shaped in any desired manner and is preferably provided with a rough surface by means of which the match can be easily scratched.

Suitable receptacles are attached to the device for receiving the burned matches and ashes, which receptacles are readily detachable for the purpose of cleaning them.

It will thus be seen that I provide an exceedingly cheap, simple, and efficient combination match-box or safe, cigar-cutter, and ash-receptacle.

Having thus described my invention, what I claim as new, and desire to secure by Letters Patent, is—

In a combined match-safe and cigar-cutter, the combination with the box or casing having a hopper at the upper end, a catch-chamber at the lower end and an intermediate chamber, of the vibrating feed-drum journaled in said intermediate chamber, the mutilated pinion arranged upon the end of said drum, the plunger-rod having rack-teeth adapted to engage the said mutilated pinion, and having a blade at its lower end, the spring for returning the said plunger-rod to its normal position, the side of the catch-chamber having openings produced therein below the cutting-blade of the plunger-rod, substantially as shown and described.

FREDERICH ALEITH.
